FRUIT TREATING MACHINE

Bronson C. Skinner, Dunedin, Fla., assignor to
Feed Machinery Corporation, San Jose, Calif.,
a corporation of Delaware

Application August 30, 1933, Serial No. 687,536

5 Claims. (Cl. 146—202)

This invention relates to a machine for washing and polishing fruits, vegetables or any rollable articles and relates particularly to certain adjustable features that tend to greatly affect the efficiency and generally satisfactory operation of machines of this type.

The machine to which this invention is particularly adapted comprises brushing rolls of any suitable character for the work in hand that are arranged in parallel relation and over which the articles to be treated are adapted to roll.

Adjacent the brush or polishing rolls are what is technically termed, "rubboards". These are members arranged over and somewhat to one side of the brush rolls and lie parallel therewith and together with the rolls form valleys through which the articles roll as they are being treated. These "rubboards" have usually been made in comparatively short sections with individual adjustment relative to the brush rolls to modify the character of the valley formed for the articles to roll along according to the size of the articles.

Much difficulty in operation has been encountered due to the manner of adjustment of these rubboards, the single board adjustment requiring the manipulation of a plurality of adjusting means to get them all adjusted alike.

There are several reasons for the frequent necessity of adjustment and among the most important are the changing size of fruit or product being handled; the character of the work being done, washing or polishing, and the efficiency of the results being accomplished.

In efficient operation the product should be made to lie in the valleys formed by the brushes and the rubboards so that the product is being constantly turned and rolled so that all surfaces are contacted with the brushes to effect the desired cleaning or polishing, and without bouncing the fruit which might have a tendency to bruise or otherwise injure it.

The rubboards are normally covered with a cloth material so that there will be a slight scrubbing action as the product is rolled by the brushes and to provide a somewhat soft surface for the contact so that damage will not result to delicate skinned fruits or vegetables.

These machines are usually quite long, sometimes in the neighborhood of eighteen feet, so that it has required a considerable number of the individual rubboards to cover this area, and an equal number of individual adjusting means to place all the boards in the proper positions.

The principal improvement disclosed by this

application refers to the manner of making the rubboards and the manner of adjusting them.

In this invention there is only one rubboard for each washing or polishing brush and this one board extends the entire length of the machine. 5

In a machine having two parallel brushes as illustrated in the drawings, two rubboards will be provided. These rubboards are so mounted that they will swing out over the brushes when they are adjusted and thus change the valley the entire length of the machine with only one adjusting means.

The adjusting means is so arranged and mounted together with the cooperating elements, that the simple turning of a single adjusting screw 15 will immediately adjust both the rubboards the same amount for the entire length of the machine and for both sides of the machine.

This improved adjustment enables the packer to instantly adjust the machine to make corrections disclosed by the condition of the product as it is discharged, which would be practically impossible with the old arrangement of individual boards. 20

It is therefore an object of the invention to 25 provide a machine for washing or polishing fruits or the like wherein the efficiency of the operation may be controlled by an instantaneous adjustment.

It is also an object of the invention to provide 30 a machine for the purpose described wherein the runway or valley through which the articles roll may be changed in character while the machine is in operation.

It is also an object of the invention to provide 35 a machine for the purpose specified that will be instantly adjustable for a change in the size of the product being handled so there is no loss of time or product through delays usually incident to such changes. 40

It is also an object of the invention to provide 45 a machine for washing and polishing fruits or the like wherein a change in speed of the brushing elements instantly converts the machine from a washer to a polisher and in providing adjustment means for instantly correcting the angle and shape of the fruit runway or valley so that it will work most efficiently with that size of article.

With such objects in view as well as other advantages that may be inherent in the invention, consisting in the parts and combinations hereinafter set forth, it is understood that the several necessary elements, parts and combinations constituting the same may be varied in their pro- 50 55

- portions, placement and general arrangement without departing from the nature and scope of the invention, and in order to make the invention more clearly understood there are shown, 5 somewhat diagrammatically in the accompanying drawings, means and mechanism for placing the same in the preferred form without limiting the improvements in their application to the particular construction shown.
- 10 The drawings are not necessarily made to scale and some parts may be exaggerated more or less relative to other parts to better illustrate the invention. They are to be considered merely as illustrative and not necessarily technically correct working drawings.
- Figure 1 is a plan of a machine embodying the preferred form of the invention with the center section of the machine broken away to shorten the view.
- 20 Figure 2 is a plan of Figure 1.
- Figure 3 is a cross sectional elevation taken on substantially the line 3—3 of Figure 1.
- Figure 4 is a detail of one of the rubboard supporting brackets.
- 25 Figure 5 is a detached view of the mechanism carrying the rubboards and the adjustment thereof.
- Figure 6 shows an end view of the rubboards and supporting brackets.
- 30 Figure 7 is plan view of one of the adjusting cams.
- A pair of long brush rolls 1 are mounted in a suitable framework to be rotated by suitable power means comprising the cross shaft 2 carrying bevel gears 3 meshing with pinions 4 on the ends of the brush roll shafts 5.
- The two brush rolls are mounted parallel and spaced apart as shown in Figure 3. A plurality of standards 6 are secured along the framework 40 and act as the main supporting means for the rubboard mechanism.
- 45 Adjustably carried by the standards 6 are a series of members 7 secured to tie bars 8 which bars extend from end to end of the machine. The members 7 have vertical adjustment relative to the members 6 by means of the adjusting screws 9. By means of the screws 9 the proper vertical placement of the entire rubboard mechanism is accomplished.
- 50 On the tie bars 8 are mounted a series of brackets 10 through the medium of the bushes 11 which form long bearings for the brackets 10 to hold them in proper alignment.
- Figure 6 shows the end shape of the brackets 55 10. Extending from bracket to bracket throughout the length of the machine are angle bars 12 that rest in the ways 13 of the brackets 10 and are tied together by means of the adjusting member 14 which is securely bolted to the rails 12 as is clearly shown in Figure 2.
- One of the brackets 10 carries an extension 15 which in turn is connected to the adjusting screw 16 which in turn moves in the fixed nut 17 carried by the spanning member 14.
- 65 A series of cams 18 and 19 are adjustably mounted on the rails 12 where they rest in the ways 13 of the brackets 10. These cam members have cam grooves in opposed relation as at 20 and 21, the purpose of which will be explained.
- In the open spaces of the brackets 10 are mounted on the upper rod 8, a series of hanger members 22 which are arranged in right and left relation in each bracket 10. These hanger members carry the long rubboards 23, one to operate

with each brush roll. Figure 4 shows one of the hanger members with the rubboard attached. The upper ends of the hanger members 22 carry the rollers 24 which ride in the cam grooves 20 and 21, the action of which will be explained.

The rubboards 23 are preferably covered with a fabric or other soft material as shown at 25.

Operation

An operative description will give details not 10 before referred to.

As has been mentioned, when machines of this type are in operation there is quite a large amount of product passing continuously and if the operator discovers that either the washing 15 or polishing is not being done satisfactorily on account, possibly of a slight misadjustment of the rubboards relative to the rotary brushes, he may with this improvement instantly correct the adjustment along the entire length of the machine 20 and on both sides at the same time.

The adjusting screw is mounted in the fixed bracket 15 for rotation but against axial movement so that when the screw 16 is turned the effect is to move the nut 17 and spacer bracket 25 14 either toward or away from the extension 15, and this in turn will move the angle rails 12 on which are mounted the cams 18 and 19, when they will be moved accordingly. The rollers 24 riding in the cam grooves 20 and 21, will on account of the longitudinal movement of the cams, be moved to swing the members 22 to which are secured the rubboards 23. This swinging movement being uniform and equal throughout the machine the rubboards will immediately assume 30 35 the new positions to increase or decrease the rubbing action of the brush rolls.

If the rubboards are moved away from the brushes toward the center of the machine the valleys formed by the brush surfaces and the rubboards will be deepened, so to speak, and the articles will bear harder against the brushes and will be brushed or polished more vigorously, while if they are moved toward the brushes or away from the center of the machine the valleys 45 will grow shallower and the articles will not be brushed so vigorously.

The great efficiency of this device over any prior methods of adjusting the machine for these operations, lies in the quickness that the adjustments may be made without stopping the machine or interfering in any manner with the continual flow of articles through the machine.

Another reason for desiring a change in adjustment is when the size of the fruit changes. If the machine has been running on small fruit the valleys between the brushes and the rubboards will be somewhat shallow, then if a change is suddenly made to larger fruit the adjustment may be made before the fruit has hardly started along the valleys and the valleys made deeper to accommodate the larger fruit.

It will be noted that the cams are arranged in reversed pairs for each pair of swinging members 22 so that either direction of movement of 65 the cams will effect a like movement of all of the swinging members and thereby produce a simultaneous movement of both rubboards, which are at all times held parallel with the brushes.

The vertical adjustment provided for the entire 70 rubboard mechanism is not necessarily used for operative adjustments but is rather an adjustment that is made when first setting the machine, and while adjustment in a vertical direction may be desirable at times to accommodate certain 75

product, the longitudinal adjustment is the one that is made while the product is rolling through the machine.

To convert the machine from a washer to a polisher is only a matter of changing the rotary speeds of the brush rolls.

The longitudinal adjustment provided in the cams 18 and 19 is for the purpose of aligning the swing members 22 when they are bolted to the rubboards 23. This adjustment is by means of the slotted holes so the cams may be moved along the angle rails until the desired setting is reached when they will be secured permanently and need no further adjustment.

15 What I claim as new and desire to secure by Letters Patent, is:

1. A machine for brushing and cleaning a product such as fruit or any rollable articles comprising a pair of brush rolls arranged in parallel 20 relation, rubboards positioned between said rolls and inclined relative thereto to form with said rolls, article runways along which the product rolls while being brushed, a pivot bar and a guide bar extending lengthwise through said machine 25 above and parallel with said rolls, swinging arms mounted on said pivot bar for supporting said rubboards, fixed brackets mounted on said pivot and guide bars, cam plates mounted to slide through said brackets and a single means for 30 moving said cam plates at will, cam grooves associated with said plates for engaging said pivoted swinging arms to swing them and thereby reposition them and the rubboards relative to 35 said rolls, when said plates are moved.

35 2. A machine for brushing and cleaning a product such as fruit or any rollable articles comprising a pair of parallel arranged brush rolls, rubboards mounted above and at one side of said rolls to form article runways therewith, fixed brackets 40 mounted above and between said rolls, guide bars supporting said brackets, swinging arms mounted on one of said guide bars and acting as supports for said rubboards, cam plates mounted to slide 45 through said brackets and connected for simultaneous movement, a single means connected with said cam plates for moving them at will, cam grooves associated with said cam plates, extensions on said swinging arms engaging in said cam 50 grooves and moved thereby when said cam plates

are moved to thereby change the relative positions of said rubboards and brush rolls.

3. A machine for brushing and cleaning a product such as fruit or any rollable articles comprising a pair of brush rolls arranged in parallel relation, rubboards positioned above and at one side of said rolls to form therewith runways for the product being handled, fixed brackets mounted above and between said rolls and having guideways therein, lengthwise bars 5 for supporting said brackets, a series of cam plates mounted on slide bars and adapted to slide in the guideways in said brackets, a single adjusting means carried by one of said brackets and connecting with said cam plates to move 10 them at will, cam grooves associated with said cam plates, swinging arms supporting said rubboards, extensions on said arms engaging with said cam grooves whereby said arms are swung on their pivots when said cam plates are moved 15 by said single adjusting means to thereby change the relation between said rubboards and said rolls.

4. A manner of adjusting the rubboards of fruit or other product brushing and cleaning machines comprising swinging arms for supporting the rubboards, a single pivotal support for all of said arms, a series of cam plates, guide bars for supporting said cam plates, guideways for said guide bars to slide in, a single means for adjusting said cam plates to move parallel with said 25 rubboards, cam grooves associated with said cam plates engaging said swinging arms whereby all of said arms are given pivotal movement when said cam plates are given lineal movement thereby changing the relative positions of said rubboards.

5. An apparatus for adjusting the rubboards of fruit brushing and cleaning machines comprising swinging arms for supporting the rubboards, 40 a single pivotal support for all of said arms, a series of cams, guide bars for supporting said cams, guideways for said guide bars to slide in, a single means for adjusting said cams to move parallel with said rubboards, said cams engaging 45 said swinging arms whereby all of said arms are given pivotal movement when said cams are given lineal movement thereby changing the relative positions of said rubboards.
